CHARGE FORMING DEVICE

Courtney N. Mitchell, Berea, Ohio

Application October 21, 1927, Serial No. 227,692
Renewed May 5, 1934

4 Claims. (Cl. 123—127)

This invention relates to improving the performance of internal combustion engines, and more particularly to that type using carburetors or other devices for mixing the fuel with the air or oxygen to support combustion. However, it will be evident from the following that a device of this kind would be very useful in forming a preliminary combustible charge in an injection type of engine, such as the commonly known Diesel, and thus securing improved performance. The main object of the invention is to secure maximum performance by improving the combustible mixture. However, a fan or blower connected to the auxiliary air inlet to raise the pressure there applied to some amount above the atmospheric pressure has some advantage and such a device can be connected easily. Another object of this invention is to provide means for introducing additional fuel with this air or simultaneously therewith in order to maintain the correct proportions for efficient combustion. A further object is to provide means for introducing water or water vapor into the intake manifold for the purpose of increasing the humidity of the atmosphere therein which adds to the smoothness of engine operation by retarding the rate of combustion, thus preventing or reducing the tendency to "knock" or detonate and reducing the tendency for the formation of carbon deposits in the combustion space. Another object is to provide a means of securing approximately atmospheric pressure in the manifold closely adjacent to the throttle valve, thus securing additional mixture to maintain higher velocities at the desired parts of the manifold. A still further object is to provide a means whereby the distribution of the mixture to all cylinders of a multi-cylinder engine may be maintained equally. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a side elevation of the device as installed in the section of the engine manifold between the carburetor and the distribution header of the manifold; Fig. 2 is a vertical transverse section taken on line 2—2 of Fig. 1, and looking in the direction of the arrows; Fig. 3 is a longi-

tudinal section taken on line 3—3 of Fig. 2, and looking in the direction of the arrows; Fig. 4 is a portion of the upper tank of an automobile radiator showing means for taking off water vapor from the space above the water in this tank; Fig. 5 is a transverse section similar to Fig. 2 and showing an alternative form built up from several parts and using a different method of fuel and air control; Fig. 6 is a transverse, approximately horizontal section, taken on line 6—6 of Fig. 5, and looking in the direction of the arrows; and Fig. 7 is a fragmentary section similar to Fig. 5, but showing an alternative means of control; Fig. 8 shows a further modification of the device.

Referring to the invention as illustrated by Figs. 1, 2, 3 and 4, the figure 8 designates the carburetor which is attached to manifold 9 into which manifold the elements are constructed which constitute a part of the present device.

Adjacent the carburetor attachment flange 10 and in such a position relative to the stream line flow of the carburetor mixture as to discharge into a region of extremely low pressure, is located an air delivery valve 11 which will be referred to as a "booster". This booster consists of a cone seated or needle valve 12 having spring seat 13 attached to its stem. This spring seat 13 fills most of the sectional area of the booster housing 14, thus acting as a piston or air valve. The valve 12 is held normally out of contact with its seat 13 by means of the spring 16, thus permitting air to pass through slotted openings 17 along the stem 18 and past the edge of spring seat 13 and valve 12 into the manifold.

When the engine is operating with closed or nearly closed throttle, the pumping action of the engine pistons produces a very material vacuum in the manifold and the atmospheric pressure will thus close booster 11 forcing valve member 12 into contact with its seat 15 through the pumping effect acting on disc member 13, and overcoming the relatively light pressure of spring 16. This action prevents an excess of air entering the combustible mixture at low speed and light load conditions which would tend to produce erratic action of the engine. When the carburetor throttle valve is opened wide, or to a material degree, the pressure rises in the section of the manifold adjacent to the throttle valve to a point only a little below the outside air pressure. This increase in pressure permits spring 16 to open valve 12 and the pressure difference permits an appreciable amount of air to enter through valve seat 15. By locating the

booster unit 11 at a point close to the wall of the manifold having the least radius of curvature and well around the curve and away from the stream line flow of elements leaving the carburetor, as shown in Fig. 3, a pressure somewhat below the average for that section will be found and a greater amount of air will thus be introduced by booster unit 11, than would be possible if it were located elsewhere. This booster thus permits of the use of more fuel at high speed and full load and will therefore add to the total power output. By the addition of more air by means of carburetor adjustment the explosive mixture may be somewhat reduced in strength at higher speeds and a material increase in the economy of operation thus obtained.

At some distance from the carburetor the sectional area of the manifold is reduced forming a section commonly known as a venturi or diffuser 20 as illustrated at 19. Entering the manifold at the throat or smallest diameter of this diffuser is another air delivery valve 20 and which is similar to booster valve 11 but differently operated. Its parts are substantially identical in size 25 and shape to those of booster 11. Valve 21 corresponds to valve 12, 22 corresponds to spring seat 13, 23 corresponds to housing 14, 24 corresponds to seat 15, and spring 25 is similar to 16, but has a different load rating. Air slots 26 correspond to slots 17 and valve stem 27 is identical with stem 18, save that it is of greater length. The valve 21 is normally held in closed position by means of lever 28 which is actuated through a linkage 29 from the carburetor throttle lever 30. Lever housing 31 is threaded to valve housing cover 32 and through it and the tube elbow fitting 33 and tube 34, humidified air is introduced to the manifold when valve 21 is off its seat.

The upper end of tube 34 is attached by sleeve nut 35 to hollow bolt 36 into one end of which is soldered inlet tube 37. Bolt 36 is held in place in the wall of radiator hose 38 by means of washers 39 and 40 and nut 41. Air enters the radiator tank 42 through the overflow pipe 43.

In order to supply additional fuel for the air furnished by the booster 11 and the air delivery valve 20, a metering valve 44 is provided through which fuel is carried from the carburetor float chamber 45 and tube 46 and introduced around valve 21 with the humidified air. This valve is connected by link 47 with lever 28 whose position in turn is controlled by the carburetor throttle lever as pointed out above, the fuel valve opening thus being controlled by the carburetor throttle and air admission valve connected thereto.

From the foregoing description it will be understood that when the carburetor throttle valve is opened to secure maximum engine output, not only does booster 11 add to the available air in the manifold as described, but through linkage connections with the throttle valve lever the pressure of lever 28 on the end of valve stem 27 is released and spring 25 opens valve 21 permitting water vapor to pass into the manifold. Due to the reduction in diameter of the manifold forming the venturi 19, the velocity at the throat of this venturi is increased to several times the velocity in other sections of the manifold and in accordance with Bernoulli's theorem, this increase in velocity is accompanied by a corresponding decrease in pressure to a value very much below atmospheric pressure. By arranging a gradually divergent opening from the throat of the venturi into the section of the manifold above or beyond the venturi, this very high velocity head of the

gas mixture will be converted back into pressure head.

This alternate reducing and increasing of the pressure in the manifold aids in the vaporizing of the fuel and increases the capacity of the supporting air to carry along more evenly the unvaporized elements resulting in a better distribution of power from the various cylinders of a multi-cylinder engine. The reduction in pressure and increase in velocity at each successive venturi causes a further vaporizing of liquids in the gas stream and a breaking down into smaller particles the globules carried by the stream.

Figs. 5 and 6 illustrate an alternative arrangement which is desirable when it is necessary to introduce greater quantities of additional air or where more accurate metering of the air and fuel is required.

In Fig. 5 booster valve 48 is identical with that shown at 11 in Fig. 2 and serves the same purpose. The diffuser or venturi 49 is introduced into the manifold 50 as a separate piece which is separate from the carburetor elbow 51. The external part of this diffuser 49 is turned down so as to form an annulus or circumferential distributing chamber 52 through which, by means of holes 53, air from valve box 54 and fuel from valve 55 is introduced. Valve box 54 is provided with a screen cover 56 and a valve 57 which is controlled by lever 58. Fuel valve 55 is controlled by lever 59 which is connected to air valve lever 58 by link 60 which in turn is connected to carburetor throttle lever 61 by means of link 62. When the carburetor throttle valve is opened wide or to a position giving approximately full power, valve 57 is opened to provide the additional air and fuel valve 55 connected thereto is likewise opened to provide the necessary additional fuel. The construction of a separate Venturi member is very advantageous as it makes possible the polishing of the inner surfaces more effectively than is possible with the integral construction and permits the use of a large number of accurate inlets to the Venturi throat.

In order to secure a further air delivery and obtain the maximum amount of pressure adjacent to the engine intake valve, a second venturi 63 is located in the manifold and cylinder as shown. This venturi is very similar to the former 49 and is provided with a source of humidified air coming through tube 64 and controlled by valve 65 which may be operated from the steering wheel of the car or so connected as to function automatically.

In order to make the operation of the air delivery valve automatic and independent of any external connections, the air and fuel flow may be controlled by the gas velocity in the manifold itself as shown in Fig. 7. It is to be understood that the tubular element shown in Fig. 7 is adapted to be mounted in the manifold line in the same relative position as the element in Fig. 5 in which is mounted the venturi 49. That is, this tubular element has its lower end connected to an elbow in which is mounted a valve similar to the valve 48 of Fig. 5. The venturi is arranged substantially as shown in Fig. 5 already described and a fitting substantially the same as 51 and containing valve 48 is shown in fragmentary form attached to the manifold member. The valve 66 has a slotted passage 67 through it, into which the end of the lever 68 projects. Attached to lever 68, or integral with it, is the disc or paddle 69 which extends partly across the manifold passage 70 thus tending to obstruct the free flow of

the combustible mixture. As the velocity of the gas past the disc 69 increases as the power output of the engine increases, the disc is rotated on its axis 71 due to the gas impinging on the lower surface of the disc and lever 68 attached to it is rotated compressing spring 72 and moving air valve 66 away from its seat 73 thus permitting air or combustible mixture contained in the annulus 74 around valve 66 to flow through annulus 75 and holes 76 into the gas stream passing the throat of venturi 77 which results from the greatly reduced pressure in the throat of the venturi as already explained.

It is evident from the construction shown that 15 the supplementary gases are taken partly from the manifold below the venturi and past the space 78 adjacent to disc 69 and partly from the air feed chamber 79 which operates automatically like the booster 11 shown in Fig. 2 and already explained. 20 In order to compensate for the lack of fuel resulting from an excess of air introduced through air feed chamber 79, an automatic fuel valve 80 is so located in relation to valve seat 73, that it is opened simultaneously with the opening of air 25 valve 66 and fuel is introduced at a rate determined by the pressure drop at the valve seat 73 and the adjustment of thumb screw 81 which controls the maximum opening of valve 80.

In compression ignition engines no carburetor 30 is employed, but ordinarily an air inlet manifold is used in which the inlet air attains velocity of considerable amount. By inserting in a branch of such air manifold a venturi similar to that shown and described above, as for instance the 35 venturi shown at 49 in Fig. 5, a substantial increase in velocity and reduction in pressure is attained at the throat of the venturi. This reduction in pressure provides a difference between the pressure at this point in the manifold and the 40 outside atmosphere, causing air or other gases from this surrounding atmosphere to enter through a suitable fitting such as 54, which will then pass through the orifices 53 and will thus be added to the stream of gases entering this 45 venturi from below.

It is well known that below the critical pressure 50 differences, an increase in the pressure of the high pressure side of an orifice produces a proportional increase in the flow through that orifice. 55 To provide this increase in pressure, the discharge pipe of a compressor or blower is connected to fitting 54 so as to deliver into this fitting and thence into annular space 52, air or other gas under the desired pressure and thereby increase 60 the delivery of fluid to this space. It will be evident that valve 51 is readily adapted to control the discharge from the blower into the annular space 52 and thence the discharge through the orifices 53 into the venturi.

The reduced pressure at the throat of the venturi provides means for making further improvements in the charge entering the cylinder. By introducing into such space at 52 of Fig. 5, any liquid capable of being vaporized or atomized, a further improvement is accomplished in the contents of the stream entering the engine cylinder. By providing a limited amount of water vapor or liquid fuel, the combustion characteristics of the 70 engine are improved. This water vapor or fuel is derived from a suitable solution delivered by valve 55 to the annular channel 52 from where it flows through passages 53 into the air stream at or very near to the throat of the venturi. Depending on the operating conditions desired, this

liquid is introduced alone or together with air entering through fitting 54.

It will be evident that as any liquid passes orifices 53 and enters the throat of the venturi, the pressure on it suddenly and very materially 5 drops. This drop in pressure together with the heat usually present in the manifold causes all or a substantial portion of this liquid to vaporize and thus to enter the main stream above the venturi and then the engine cylinder in condition 10 to participate efficiently in its function in the process of combustion. Such liquid as is not vaporized will become very finely atomized and will thus be readily carried by the air stream. As greater changes in pressure and temperature 15 are required to condense the vapor formed than were required to vaporize it, especially when the air stream is below the saturation point, there will be but a limited amount of condensation 20 after the venturi has been passed.

Fig. 8 illustrating an application of the charge forming device for use on a compression ignition engine of the Diesel type as referred to above, shows a construction similar to that of Fig. 5. In this embodiment the inlet valve 83 controls the 25 flow of air from the intake piping to combustion chamber 84. This piping comprises the fitting 85 which is made in the form of an elbow as shown or in numerous other shapes to adapt it to the space available. Within this fitting is 30 the venturi 86 having annular channel 87 to which auxiliary air from air fitting 88 is delivered under desired pressure. Several passages 89 deliver this auxiliary air to the main stream which passes thru fitting 85.

A centrifugal blower of similar device indicated at 90 preferably having two outlets, delivers air under considerable pressure to manifold 91, having passages 91' and 91'' from which the air is delivered thru valve housings 92 and 93 to fittings 88 and 85. Valves 94 and 95, which are preferably interconnected, control the delivery and distribution of air to the above fittings. By this means air under one condition of pressure is delivered to fitting 85 and air under another pressure is 45 delivered to the annular channel 87.

In order to modify the combustion in chamber 84 an auxiliary fluid such as water vapor or other fluid is introduced through fitting 96, the flow of which is regulated by valve 97. The venturi 98 having passages 99 serves to facilitate the 50 delivery of this auxiliary fluid which is maintained at any desired pressure.

Other modes of applying the principle of my 55 invention may be employed instead of the one explained, change being made as regards the mechanism herein disclosed, provided the means stated by any of the following claims or the equivalent of such stated means be employed.

I therefore particularly point out and distinctly claim as my invention:

1. In combination with an internal combustion engine including an intake valve, an intake manifold, and a carburetor, a connection between said manifold and said carburetor, automatically actuated means for admitting auxiliary air to said connection, manually actuated means for admitting auxiliary air to said connection, and manually actuated means for admitting additional fuel to said connection.

2. In combination with an internal combustion engine including an intake valve, an intake manifold, and a carburetor, a connection between said manifold and said carburetor, automatically actuated means for admitting auxiliary air to said 70 connection.

connection, a valve housing communicating with said connection, a manually actuated valve in said housing for controlling the flow through said housing of auxiliary air, a screen protecting the 5 inlet end of said housing, and manually actuated means for admitting additional fuel to said connection.

3. In combination with an internal combustion engine including an intake valve, an intake manifold, and a carburetor, a connection between said manifold and said carburetor, automatically actuated means for admitting auxiliary air to said connection manually operable means for admitting auxiliary air to said connection, a tube 10 leading from said carburetor to a point intermediate the ends of said connection, and a manually actuated rotary valve for controlling the flow through said tube of additional fuel to said connection.

4. In combination with an internal combustion engine including an intake valve, an intake manifold, and a carburetor, a connection between said manifold and said carburetor, a curved passage 15 through said connection, an air duct entering said passage adjacent to the point of said curve having the greatest curvature, an automatically

actuated valve in said duct, a Venturi member mounted in said passage and forming an annular chamber therein, bores in said Venturi member providing communication between said annular chamber and the throat of said member, a valve 5 housing communicating through said connection wall with said annular chamber, a manually actuated butterfly valve in said housing, a screen protecting the inlet end of said housing, a tube leading from said carburetor and communicating 10 through said connection with said annular chamber, a manually actuated rotary valve for controlling the flow through said tube, means connecting said butterfly valve with said rotary valve to effect dependent operation thereof, a second 15 Venturi member in said manifold adjacent said intake valve and forming an annular chamber in said manifold, bores in said second Venturi member providing communication between said annular chamber and the throat of said member, 20 a conduit leading from a source of fluid and communicating through said manifold wall with said manifold annular chamber, a reciprocable valve in said conduit, and manually operable means to actuate said last-named valve. 25

COURTNEY N. MITCHELL.
